UNITED STATES PATENT OFFICE.

JOHN DUDLEY TODD, OF MCKENZIE, TENNESSEE.

TELEPHONE MUFFLER.

Application filed March 28, 1922. Serial No. 547,448.

To all whom it may concern:

Be it known that I, JOHN D. TODD, a citizen of the United States, residing at McKenzie, in the county of Carroll and State of 5 Tennessee, have invented a new and useful Telephone Muffler, of which the following is a specification.

This invention relates to sound deadening devices or mutes, the primary object of the 10 invention being to provide a device of this character for use in connection with the alarm bells of a telephone or the like.

A further object of the invention is to provide a device of this character which may be 15 positioned in proximity to the tapper employed for sounding the bell, novel means being provided to be moved to a position between the bells and tapper, so that movement of the tapper will be transmitted 20 through a suitable sound deadening device.

Another object of the invention is the provision of a mute which may be readily and easily thrown into and out of operation at the will of the operator.

25 With the foregoing and other objects in view which will appear as the description proceeds, the invention resides in the combination and arrangement of parts and in the details of construction hereinafter described.

30 and claimed, it being understood that changes in the precise embodiment of the invention herein disclosed, may be made within the scope of what is claimed, without departing from the spirit of the invention.

35 Referring to the drawing:—

Figure 1 is an elevational view disclosing a device constructed in accordance with the present invention, as in its active position.

Figure 2 is an end elevational view of a 40 telephone coil box disclosing the invention as associated with the bells thereof.

Figure 3 is an enlarged elevational view of the device, the same being shown in dotted lines in its inactive position.

45 Figure 4 is a plan view of the device.

Figure 5 is a longitudinal sectional view through the device.

Referring to the drawing in detail, the device includes a body portion 5, having a 50 curved section 6 adapted to lie directly over the tapper of a telephone bell, when the device has been positioned.

This body portion 5 also includes forwardly extending spaced arms 7, and rearwardly extending spaced arms 8, the rear-

wardly extending arms 8 being formed with cut out portions 9. Positioned over the cut out portions 9 are sections of soft leather material indicated at 10, portions of the arms extending inwardly as at 11 to embrace the ends of the leather material 10 to secure the same to the arms 8. These leather sections 10 lie in positions to be engaged by the tapper employed in sounding the bells, which in the present showing are indicated at 12, so that the sound will be deadened and the alarm will be in the form of a buzzing noise, deadening the vibrations of the bell.

The supporting section of the device is 70 formed of a strip of metal embodying a curved section 13 and rearwardly extended arms 14 disposed in spaced relation to provide means for pivotally connecting the body portion 5 to the supporting section, 75 pivot means being illustrated at 15. Forwardly extending ear 16, forms a part of the supporting section, and is provided with an opening to accommodate a suitable securing means, a rearwardly extending ear being also formed at 17 to accommodate a suitable securing means, whereby the supporting section may be secured to a telephone bell box.

It might be further stated that the width 85 of the body portion and supporting section is equal to the distance between the ordinary alarm bells of a telephone, to permit the device to be readily and easily positioned therebetween.

In the use of the device, if it is desired to move the body portion to its active position, it is only necessary to swing the same downwardly from the position as indicated by Figure 3 of the drawing, as shown in dotted lines, to the position as shown in full lines. Thus it will be seen that the leather sections 10 are brought directly opposite to the tapper, to the end that the tapper does not contact with the bells proper, but engages the leather sections. It follows that the sound is deadened, but is sufficient to give the necessary alarm. When it is desired to permit the tapper to contact directly with the bells, it is only necessary to swing the body portion to a position as shown in dotted lines in Figure 3 of the drawing.

Having thus described the invention, what is claimed as new is:—

1. In combination with the bells and tap-

per of a telephone signal box, a sound deadening device comprising a body portion adapted to be positioned between the bells, and means carried by the body portion and 5 adapted to be engaged by the tapper, to restrict vibrations of the bells.

2. In combination with the bells and tapper of a telephone sound box, pivoted means disposed between the bells and adapted to 10 lie within the path of travel of the tapper for restricting movement of the tapper.

3. In combination with the bells and tapper of a telephone sound box, a sound deadening device comprising a supporting ele-

ment adapted to be secured in a position directly over a tapper, a pivoted body portion carried by the supporting element, and said body portion carrying strips of leather adapted to lie within the path of travel of the tapper in its movement towards the bells. 15 20

In testimony that I claim the foregoing as my own, I have hereto affixed my signature in the presence of two witnesses.

JOHN DUDLEY TODD.
